United States Patent Office

Des. 228,913
Patented Oct. 30, 1973

228,913

FAN

Theodore A. Fulton, Seattle, Wash., assignor to
Flex-A-Lite Corporation, Tacoma, Wash.

Filed Aug. 3, 1972, Ser. No. 277,632

Term of patent 14 years

Int. Cl. D23—04

U.S. Cl. D23—165

FIG. 1

FIG. 2

FIG. 1 is a view of one face of a fan showing my new design;

FIG. 2 is a view of the other face of the fan; and,
FIG. 3 is an end view of the fan.

I claim:

The ornamental design for a fan, substantially as shown.
